UNITED STATES PATENT OFFICE.

EDWARD PARO, OF CHICAGO, ILLINOIS.

BELLOWS.

No. 887,118.

Specification of Letters Patent.

Patented May 12, 1908.

Application filed January 20, 1908. Serial No. 411,726.

To all whom it may concern:

Be it known that I, EDWARD PARO, a citizen of the United States, residing at Chicago, in the county of Cook and State of Illinois, have invented certain new and useful Improvements in Bellows, of which the following is a specification.

Bellows, as commonly constructed, have a nozzle attached or connected to the leather or flexible sides of the air chamber, and this construction has the defect that leaks are apt to occur where the said flexible material is joined to the nozzle.

The object of the present invention is to avoid this defect, and this object is effected by mounting the nozzle upon one of the plates, with a hole therethrough leading to the nozzle.

The invention is illustrated in the accompanying drawings, in which

Figure 1 is a plan view of a bellows so constructed. Fig. 2 is a side view partly in section. Fig. 3 is a detail of the nozzle removed from the bellows.

Referring specifically to the drawings, 6 and 7 indicate the top and bottom plates respectively, having handles 8 at their rear ends and connected by the leather or other sides 9 forming the air chamber. The plates 30 are movable toward and from each other to expand and contract the bellows in the usual manner.

The nozzle 11 is mounted upon one of the plates. It has a base 10 which projects laterally to afford room for screw holes whereby it may be attached to the top of the plate,

and it has a depending nipple 13 which fits within a hole formed in the plate 6 to receive it. One of the plates has the usual inlet valve 14 therein, and the nozzle has a suitable outlet valve 15 therein, which operate in a well known manner.

By the construction shown the leather sides 9 may extend continuously around the plates and have no joints subject to wear and strain incident to the manipulation of the device. In the old construction the continued bend of the leather where it was joined to the nozzle piece soon resulted in cracks and leakage around the mouth, but by mounting the nozzle upon one of the plates this objectionable result is avoided, and the bellows will last indefinitely. The construction is also considerably cheaper, and particularly a saving of time and labor is effected in assembling the parts.

I claim:

A bellows provided with a hole in one of the plates thereof, and a nozzle comprising a base mounted on the plate and fastened thereto around said hole, a nipple projecting inwardly from the base into said hole, a pipe projecting outwardly from the base, and an outlet valve in the nozzle, between the nipple and the pipe.

In testimony whereof I affix my signature, in presence of two witnesses.

EDWARD PARO.
